UNITED STATES PATENT OFFICE.

WILLIAM H. PEARSON AND TIMOTHY J. KELLY, OF PASSAIC, NEW JERSEY, ASSIGNEES
TO BRIGHTON MILLS, A CORPORATION OF NEW JERSEY.

MACHINE FOR UNITING THREADS OR CORDS.

Original application filed April 12, 1921, Serial No. 460,725. Divided and this application filed December 1, 1921. Serial No. 519,257.

To all whom it may concern:

Be it known that we, WILLIAM H. PEARSON and TIMOTHY J. KELLY, citizens of the United States, residing at Passaic, in the county of Passaic and State of New Jersey, have made certain new and useful Improvements in Machines for Uniting Threads or Cords, of which the following is a specification.

10 The invention relates to a novel mechanism for uniting threads or yarns in weaving or other textile or cordage work while avoiding forming a knot therein which involves the entire thread or yarn and maintaining or reestablishing at said juncture or place of union the amount or degree of twist which is normal or standard for the remainder of the thread or yarn.

Objects and advantages of the invention 20 will be set forth in part hereinafter and in part will be obvious herefrom, or may be learned by practice with the invention, the same being realized and attained by means of the instrumentalities and combinations 25 pointed out in the appended claims.

The invention consists in the novel parts, constructions, arrangements, combinations and improvements herein shown and described.

30 The accompanying drawings, referred to herein and constituting a part hereof, illustrate one embodiment of the invention, and together with the description, serve to explain the principles of the invention.

35 Of the drawings:—

Fig. 1 is a top plan of a machine or mechanism embodying the invention;

Fig. 2 is a side elevation looking at Fig. 1 from the bottom of the sheet;

40 Fig. 3 is an enlarged, fragmentary detail of one of the thread holding clamps shown at the right-hand end of Fig. 1;

Fig. 4 is an enlarged detached, end elevation of the head of the winding reel shown 45 at the upper central part of Fig. 1;

Fig. 5 is a vertical, transverse section, taken on the line 5—5 of Fig. 1, looking in the direction of the arrows;

50 Fig. 6 is a vertical, transverse section, taken on line 6—6 of Fig. 1, looking in the direction of the arrows;

Fig. 7 is an enlarged vertical, transverse section taken on the line 7—7 of Fig. 1, looking in the direction of the arrows;

Figs. 8 and 9 are fragmentary top plans, 55 similar to Fig. 1, but somewhat diagrammatic, showing steps in the uniting of the threads;

Fig. 10 is a fragmentary detail, largely in section, of a different form of control 60 for the twisting mechanism;

Fig. 11 is a fragmentary view, partly in section and partly in vertical elevation of a combined thread-uniting and winding mechanism; 65

Fig. 12 is a fragmentary elevation, looking at Fig. 11 from the left;

Fig. 13 is an enlarged, fragmentary detail on line 13—13 of Fig. 11;

Fig. 14 is a fragmentary detail of one 70 form of device for lifting and supporting a reel or spool;

Fig. 15 is a section on line 15—15 of Fig. 14; and

Fig. 16 is a detached detail of one form 75 of spool lifting device.

This application is a division of our pending application Ser. No. 460,725 filed April 12, 1921.

In the weaving of many kinds of fabrics, 80 and in other textile or cordage work, it is advantageous or essential that the ends of two threads or yarns be firmly and positively united without knots or like protuberances or irregularities and that the 85 threads or yarns at the place of such union or juncture be maintained of substantially the normal or standard size and strength of the remainder of the thread or cord by reestablishing at the place of union the 90 normal or standard amount or degree of twist.

The present invention provides a novel mechanism for effecting the above-described function or operation in a positive, exact, 95 easy and expeditious manner, and provides a novel means for and method of, effecting the same.

Referring broadly to the present preferred embodiment of the invention, there 100 are provided devices for holding each of two threads or yarns to be united at two definitely spaced-apart points, and, cooperating therewith, devices for uniformly and completely untwisting the strands composing 105 these two threads or yarns, and for positively storing or recording the number of twists so removed by simultaneously wind-

ing up another portion of one of the two threads. Means are provided for locating cuts at definite or predetermined points in corresponding strands of the untwisted parts of the two threads or yarns, these cut ends being then united by a small knot, and for so treating each such corresponding pair of strands at predetermined or equidistantly spaced-apart points along the untwisted part, without changing the length of the untwisted part. Cooperating therewith are means for exactly and positively restoring the normal or standard amount or degree of twist, by unwinding the aforesaid portion of one of the threads wherein the untwisting has been stored. All these functions are effected without any useless and harmful twisting or untwisting of other portions of the thread, cord, or like material.

Other features of the invention will be first described in connection with the following detailed description of the present preferred embodiment; and it will be understood that so far as concerns certain aspects of the invention, the features already described may be utilized apart from each other, or in other relations or combinations without departing from the invention.

The invention finds one of its chief and most valuable commercial applications in the manufacture of fabric for "cord tires" for motor vehicles for uniting, preparatory to weaving, the ends of the relatively heavy cords which constitute the warp of such tire fabrics, and the terms "thread" or "yarn" used herein will be understood to include the "cords" used in such tire fabrics.

Referring now to the details of the embodiment of the invention illustrated by way of example in the accompanying drawings, a machine is provided with a base 1, and preferably with an understructure whereby it may be readily moved from place to place to operate upon reeled or spooled threads and yarn in working position, as for example upon creels, the threads or cords from which are being supplied to a beamer or loom. Such understructure, as shown, comprises legs 2, cross-pieces 3 and wheels or casters 4, although such structure may be of any desired form.

Referring now in detail to the mechanism mounted upon the general base 1, two thread clamps 10 and 11 are provided, these clamps being conveniently, though not necessarily, paired together in their mounting, one of the clamps engaging the end of one of the threads to be united and the other clamp engaging the other thread beyond the point at which it is to be united to the first-mentioned thread.

As so preferably embodied, these clamps are supported on a base 12, which is mounted on the frame 1, and has projecting up-

wardly therefrom standards 13 and 14, in the upper ends of which there is mounted a clamp-supporting rod 15. The clamp 10 comprises a fixed jaw 16, and a cooperating spring-pressed jaw 17, which is slidably mounted along the rod 15. The clamp 11 comprises a stationary jaw 18 and a cooperating spring-pressed jaw 19, which is slidably mounted on the rod 15. A helical spring 20 is coiled in compression about the rod 15, and yieldingly presses the jaws 17 and 19, respectively, against the corresponding cooperating jaws. These clamping jaws and two cooperating clamping jaws or like devices to be later described, delimit a desired or predetermined length of two cords or threads wherein the strands are untwisted, cut separately at different points, the strands of the two threads are tied together, and the whole retwisted.

For the purpose of varying the delimited length of thread or cord, the mechanism just described is mounted to be movable to and fro on the base 1, and may be fixed in any such desired or predetermined position. As embodied, slots 22 and 23 are formed in the base 1, (Figs. 1 and 7) and pins or rivets 24 and 25 extend through these slots. At their upper ends, these pins are fixed to a cross-bar 26 above the base 1, and at their lower ends to a cross-bar 27 below the base plate 1. A set screw 29 is threaded into the cross-bar 26 and binds on the plate 12 to hold the mechanism in a desired position, to which position it has been slid along the base 1.

At the opposite end of said delimited length of the two threads or cords which are to be united, other suitable thread holding or clamping devices are provided. As embodied, a clamp 34 is provided for the free end of one of the threads, that is, to mark the delimited length at such free end. This clamp is provided with a stationary jaw 35, mounted upon a shaft 36, and with a spring-pressed jaw 37, mounted upon but movable along the shaft, and cooperating with the jaw 35. A helical spring 38 is coiled around shaft 36 in compression between the jaw 37 and a collar 39 fixed on the shaft. Shaft 36 is journaled in a bearing 40, carried on the machine frame, or on a housing 41, which may conveniently be employed to enclose certain of the mechanism which is later described.

The mechanism for holding the corresponding end of the delimited length of the other thread or cord comprises a drum 42 fixed on a shaft 43, which shaft is likewise journaled in the housing 41. Drum 42 is provided with flanges 44 and 45, between which the thread may be wound upon the drum, as later described herein. The flange 44 is provided with slots 46 into which the thread may be slipped, and by which it is clamped or held during the process of un-

70

twisting the strands and of later reimpacting the twist to the cut and tied strands by which the two threads have been united. When the retwisting is completed, the 5 thread automatically slips out of the slot 46.

In Figs. 1 to 5 the device is shown provided with power driving means, with automatic control, as desired, for the thread holding and untwisting means. In the embodied 10 form, a pinion 48 is fixed on shaft 36, and a pinion 49 is fixed on shaft 43. Intermeshing with both of these pinions is a gear wheel 50, fixed on a shaft 51, which shaft is journaled in the housing 41. A motor 52 15 may be utilized for driving the mechanism, and as shown the pinion 49 is fixed directly on the motor shaft, or the shaft 43 may be regarded as a continuation of the motor shaft.

20 Means are provided for controlling the extent of rotation or number of revolutions of the drum 42 and clamp 34, so as to entirely untwist the strand in the delimited length of the two threads or cords and to 25 stop the untwisting action at that point, and in conjunction therewith, means for restoring positively the same amount of twist to the strands after those of the two cords have been tied together. In the embodied form 30 of such means, the shaft 51 is screw-threaded as shown at 54, and a screw-threaded nut 55 travels on the shaft. The nut 55 also travels on a longitudinally movable rod 56, which is slidably mounted in bearings 57 35 and 58. The power circuit for motor 52 is provided with a pull-switch or socket 59, of any suitable construction and manner of operation, having a cord or chain 60, which is connected to a bent end 61 of the rod 56. 40 A hand lever 63 is pivoted within or on the housing 41 at 64, the lower end of the hand lever being connected to the switch cord 60 at 65. A stop 53 is adjustably carried on rod 56, with which the traveling nut 55 engages 45 to throw off switch 59. A cable 66 passes from the switch to the motor 52, and the power circuit is indicated diagrammatically at 67.

50 In accordance with one feature of the invention, the retwist is imparted to the united strands of the two threads or cords by unwinding the thread from the drum 42, and in connection therewith, means are provided for taking up or rewinding the thread unwound from drum 42. In the embodied form thereof, a spool or reel holder 75 is provided, having a shaft 76 and a seat 77 for the reel. The shaft 76 is journaled in an extension 78 from the housing 41, and fixed 55 on shaft 76 is a pulley 79. A belt 80 runs over this pulley and also over a pulley 81, fixed on shaft 43. One of the reels carrying one of the cords or threads to be united is mounted on the reel holder 75. The drive is 60 a friction drive which will pay off the thread 65

as it is wound on drum 42 and will take it up again as it is unwound from the drum. A double pole hand switch is shown for reversing motor 52, thereby manually controlling the winding movement in both directions if desired, and such a switch is shown at 82 in Fig. 1. When this switch is used, the switch 59 and the automatic controlling mechanism therefor can be dispensed with. 70

Means are provided for instantaneously 75 locating the separated points at which the respective strands of the two cords or threads are to be severed, and, as embodied, a plurality of pins 84 are placed in selected holes 85 in the base 1. The pins 84 may also be 80 used in tying the knots in the strands of the cords or threads.

The manner of operation of the hereinbefore-described mechanism is substantially 85 as follows:—

The thread or cord *x* from the spool or reel *a* has its end placed in the spring clamp 34, and the thread is then placed at the other end of the predetermined delimited length in the clamp 11. The thread *y* from the spool or reel *b* has its end placed in the spring clamp 10, and the thread is placed, at the other end of the predetermined delimited length, in one of the slots 46 in flange 44 of the drum 42. The delimited lengths of the threads *x* and *y* are thus held at both ends. 90

The lever 63 is thrown by hand, turning the current on to motor 52, and the spring clamp 34 and the drum 42 are rotated in the same direction, the cord or thread *y* winding on the drum 42 one convolution for each rotation of untwisting motion imparted to the delimited length of the threads *x* and *y*. As the untwisting movement of the mechanism begins and proceeds the nut 55 travels along the screw-thread 54, and slides along the rod 56 until it strikes the adjustable stop 53. When the nut engages the stop 53, the rod 56 is slid endwise, and switch 59 is actuated and thereby throws off the current and stops 100 the motor 52, when the strands of the delimited portions *x* and *y* of the threads or cords *a* and *b* have been completely untwisted. The stop 53 may be set by calculation or by experiment to stop the mechanism 105 just when the strands are completely untwisted. 110

The untwisted strands are then severally cut off in pairs, that is, one strand from each of the cords or threads, substantially 115 in a line with the respective indicating posts 84, so that one strand from one thread and a corresponding strand from the other thread have free ends at each post, as diagrammatically indicated in Fig. 8, and these pairs of ends *m*, *n* and *o* are tied together, respectively, as indicated in Fig. 8. 120

The operation is then reversed to put back the right degree of twist into the united strands of the two threads. In this oper- 125 130

ation, thread *b* is unwound from the drum 42, the friction drive for the spindle rewinding the cord on the spool or reel. This reverse operation of the mechanism and unwinding of the thread from drum 42 imparts a positive rotation to the thread holding or clamping flange 44 in the opposite direction from, and for an equal number of revolutions to, the untwisting motion already described, and thereby there is imparted to the tied but untwisted strands, as shown in Fig. 8, positively and accurately, the twist that was taken out of the same length of the cords or threads. When the thread is completely unwound from drum 42, it automatically slips out of the slot 46. In Fig. 9 the mechanism is shown at the close of the retwisting operation, with threads or cords *a* and *b* united and retwisted, and with the loose, cut-off ends of the strands held in clamps 10 and 34.

The reel or winder 75 may be used in conjunction with the hand-switch 82 and will take up the thread as it unwinds from the drum 42 when the switch is thrown to drive the motor in that direction, the tied-together or united strands thereby having the necessary twist imparted to them as already described. The reel 75 may be dispensed with and also the reversing switch 82, and the spool may be placed in a back-winder or any other winding device, the unwinding of the thread from drum 42 imparting the desired twist to the strands, as already described, and also restoring nut 55 to starting position. The entire splicing or uniting mechanism may be combined and operated with a back-winder as later described.

By the mechanism very small knots have been made, at separated and substantially symmetrically spaced-apart points, in the different strands and the points for the cutting and knotting together of the strands are indicated instantaneously and without any movement of the mechanism.

A positive and accurate retwist of the exact amount of the untwisting is also imparted to this part, or delimited length, of the now united threads or cords. Also by the winding action at drum 42 all useless and harmful twisting or untwisting of the adjacent part of the thread *b* has been avoided. This operation provides a united cord or thread with no appreciable knot in it, with the correct amount of twist, and having ninety per cent or more of the strength of the original cord at the splice, and all undesirable and harmful twisting or untwisting or disturbance of other parts of the thread have been avoided. The mechanism is also capable of rapid operation and is readily movable from one place to another as may be found most convenient and expeditious in use. The enumerated advantages, together with others which will be ob-

vious to those skilled in the art, are very valuable in all cord or thread uniting work, but find one special value and application in making fabric for cord tires, in which the warp consists of relatively very heavy cords, which must be very smooth and uniform, and the filler is relatively very light.

In Fig. 10 there is shown an optional form of control for the untwisting and twisting mechanism wherein the mechanism is automatically shut off when the retwist to the right amount has been imparted to the united threads. In the embodiment of Fig. 10, the switch 82 is acted on by spring 190, which is placed under compression beneath the switch when it is closed, but is sufficiently strong to throw the switch open if the switch is not held or detained in closed position. A detent 191 is provided pivoted at 192, and is yieldingly held in locking position by a spring 194. The tail 193 of the detent extends down into the path of the traveling nut 55, substantially at the end of the travel of the nut during the retwisting operation. After the switch 82 is thrown or closed to reverse the motor 52 to start the retwisting operation, the nut 55 travels toward the right in Fig. 1, and at the end of the retwisting operation it will trip the tail 193 of the detent 191, and spring 190 will throw out switch 82 and stop the retwisting operation. The mechanism will be timed to stop when the thread or cord is unwound from drum 42.

The device so far described can be used with the mechanism already described, including the pull switch 59. In Fig. 10, however, further mechanism is shown, whereby the switch 82 can be used to control or stop both the untwisting and the retwisting operations. As shown, a spring 196, like the spring 190 is adapted to throw the switch out at the other side. A detent 197 is pivoted at 198, and has its tail 199 extending down into the path of the traveling nut 55, and corresponds in its action or function to the stop 53. A spring 200 impels the detent into locking position. This mechanism would act to stop the untwisting operation in the same manner as the mechanism at the other end of the path of the nut 55 would stop the retwisting operation.

In Figs. 11 and 12 a combined thread or cord splicing and winding machine is shown, and in the embodied form the winding mechanism has a plurality of winding devices arranged side by side in the machine, the splicing mechanism being movable to and from along the winding mechanism to bring it successively into convenient operative relation with any desired winding device.

So far as concerns many features of the invention, the winding mechanism may be of any desired or convenient form, and as shown herein the reels or spools are ar-

ranged horizontally and one above another, the thread or cord being wound from an upper reel or spool to another located below it.

5 Referring now to the details of the illustrated form of winding mechanism, this is shown in end view in Fig. 11 as of double construction, that is with one set of winding mechanisms facing to the right (shown 10 in elevation) and another set of winding mechanisms, facing to the left, (shown partly in elevation and partly in section), all being mounted upon one machine frame.

15 As appears from Fig. 12, a plurality of sets of winding mechanisms or devices are arranged side by side in the machine frame, and a description of a single set or mechanism will be sufficient for all. Mounted on 20 a frame piece 90 are a pair of upwardly and outwardly extending arms 91 and 92, having their outer ends recessed, as shown at 93 and 94, respectively, to support a rod 95 upon which a reel or spool 96 is mounted loosely so that the thread may be unwound 25 therefrom.

30 Directly below the mechanism just described, as embodied, a pair of arms 97 and 98 extend from a sleeve 99, which sleeve is mounted to swing loosely on a rod or shaft 100, supported on the machine frame. The arms 97 and 98 are formed at their outer ends to hold a rod upon which the winding spool is mounted to rotate freely, the 35 rod being movable to receive and discharge the spools. As embodied, this spool-supporting rod 101 is mounted in a recess in the end of the arm 97, and a pin 102 passes through the end of the arm and the rod, the rod being thus pivoted to swing outwardly, so that the spool or reel may be 40 readily placed thereon and removed therefrom.

45 The arm 98 is cut away at its outer end (Figs. 11 and 14) to form a seat for the rod 101, and a hook 104 is pivoted at 105 on the arm 98, and is adapted to swing downwardly to hold the spool supporting rod 101 in position and to be swung upwardly to release the rod, so that the rod 50 may be swung outwardly for the purpose of changing spools as described.

55 The winding is effected in the present embodiment by means of friction wheels or discs 106, which are located just beneath a reel or spool 107, mounted upon the rod 101, when in operative position. The wheel 106 contacts with the spool or reel 107, or with the cord or thread thereon, to rotate the spool and effect the winding operation. 60 The wheel 106 is fixed on a shaft 107, journaled in the machine frame, the shaft being driven by any suitable driving means.

65 Means are provided in the embodied form for lifting the spool or reel 107 clear of the winding wheel 106 and maintaining

it in this elevated or inoperative position during the changing of spools or reels. As embodied, referring first to Figs. 11, 12 and 13, a bracket 110 extends downwardly (Fig. 13) from the support 111 for the rod or shaft 100, and journaled in this bracket is a shaft 112, to which is fixed a hand lever 113. Fixed or integral with shaft 112 is a cam 114, positioned beneath the arm 98. When hand lever 113 is drawn downwardly 70 and to the left from the position shown at the left hand side of Fig. 11, the corresponding arms 97 and 98 are swung upwardly, lifting the spool or reel away from the winding wheel 106 to convenient position for changing the spools; and by moving the hand lever 113 in the opposite direction the spool is again brought down on the winding wheel.

75 A weighted arm 115 is preferably employed 80 to press the spool against winding wheel 106 to insure effective winding contact or friction, as shown at the left in Fig. 11. The arm 115 may also be utilized, as shown at the upper right hand side in Fig. 11, to 85 hold the spool and spool holding arms in inoperative or idle position. For this purpose, the arm 115 will be swung backwardly beyond shaft 100 and will maintain the reel or spool 107 in elevated position until the 90 entire device is swung outwardly and downwardly and arm 115 is again brought beyond shaft 100.

95 In Figs. 14 and 15 a different form of mechanism is shown for lifting the spool 100 and its supporting arms for changing the spool or reel. In this form, a wedge or wedged-shaped cam 120 is mounted to slide longitudinally in a guideway 121 in the frame piece 122. A handle 122 projects 105 downwardly or outwardly from the wedge 120. Both the inclination of the cam 120 and of the guideway 121 may be utilized to effect the lifting of the spool. When the handle 123 is pulled to the left in Fig. 14 110 the spool or reel 107 will be lifted to the inoperative position, that is, to stop the winding and to permit the spools to be changed, and when the handle 123 is pushed to the right in Fig. 14, the arms 97 and 98 are 115 dropped down and the spool 107 is brought into winding relation with the winding or driving wheel 106.

120 In Fig. 12 the right-hand reel or spool 107 is shown in the raised or non-winding position, being retained in that position by its weighted arm 115. The two spools 107 to the left thereof are shown in winding position, that is, in position to be driven by the corresponding winding reels 106.

125 In the present embodiment, the thread or cord splicing or uniting machine 125 is shown mounted to slide to and fro along in front of a plurality of the winding mechanisms, thereby being brought into conven-

ient operative relation with any desired one of the winding mechanisms, and for this purpose, supporting and guiding bars 126 and 127 are disposed longitudinally along the frame of the machine. Bars 1261 and 1271 are employed to impose proper tension upon the thread as it is wound upon the spool 107. A reciprocating thread guide 128 is also usually employed to lay the thread evenly along the spool as it is wound thereon.

In this embodiment, the uniting machine 125 is mounted upon and so as to slide along the guide bars 126 and 127, whereby it may be used to unite the threads or cords therefor, and may be slid in front of any one of the winding devices, and may be used to unite the threads or cords therefor, and may then be slid in front of another of the winding device for this purpose, and so on to and fro from one winding device to the other as may be required in the work.

In the present form, the base 130 of the thread uniting machine is extended, and the guide bars 126 and 127 are so positioned that the base 130 rests upon bar 126 and beneath bar 127; thereby forming the desired slideable support for the thread uniting machine. The thread uniting machine shown in Fig. 11 is of somewhat different form or appearance from that shown in Fig. 1 (the particular features of which are set forth in a pending application, Ser. No. 488,178), but the machine of Fig. 1 could be mounted in the same manner by extending the base 1 thereof as shown at 131 and omitting the legs upon which the machine is mounted as shown in Fig. 2.

The mechanism renders the work of winding much more easy and expeditious and enables an operative to serve a larger number of winding mechanisms. It leaves the operative free to watch the winding mechanisms and to have both hands free for the work of uniting the threads or cords. The splicer may by a simple movement of the hand be positioned with respect to any particular winding mechanism. The thread uniting mechanism need not be supported by the operative nor does it require floor space nor to be moved about the floor from place to place.

In Fig. 16, and at the right in Fig. 11, a damping or braking device is shown for preventing the spool of thread 107 coasting or spinning as it is lifted from the friction driving roll 106. In connection therewith is shown a somewhat different form of the spool lifting cam, although the spool brake could be applied to any of the spool raising devices. In this form of the spool raiser, a sliding cam 140 is slidably supported in a channeled guideway 141, supported on a bracket 142 fixed to the frame. This cam 140 engages beneath the arm 98 in the same

manner as cam 120, already described. A rod 143 extends outwardly whereby the cam 140 may be slid to and fro to let the spool down onto the driving roll 106 or to lift it therefrom. A leaf spring 144 is fixed to cam 140 and extends outwardly into frictional contact with the spool 107 and acts as a brake to prevent spinning or coasting of the spool when it is off the friction wheel 106.

The invention in its broader aspects is not limited to the specific mechanisms shown and described but departures may be made therefrom within the scope of the accompanying claims without departing from the principles of the invention and without sacrificing its chief advantages.

What we claim is:—

1. In a machine for winding and uniting threads, the combination of a plurality of supply spools located side by side on an upper level, a corresponding plurality of winding spools located side by side on a lower level, devices which may be rendered individually inoperative, for rotating the winding spools, a guideway extending along in front of the spools, and a thread uniting device which untwists and retwists the threads as a part of the thread uniting operation, movable back and forth along the guideway at a still lower level.

2. In a machine for winding and uniting threads, the combination of a plurality of supply spools located side by side on an upper level, a corresponding plurality of winding spools located side by side on a lower level, devices which may be rendered individually inoperative, for rotating the winding spools, a guideway extending along in front of the spools, and a thread uniting device which untwists and retwists the thread as a part of the thread uniting operation, and provided with means for automatically releasing the united thread, movable back and forth along the guideway at a still lower level.

3. In a machine for winding and uniting thread, the combination of means for holding a plurality of supply spools for rotation on a horizontal axis, means for holding a plurality of winding spools for rotation on a horizontal axis, means for driving the winding spools, means for rendering the driving means for a particular winding spool inoperative as desired, and a thread uniting device which untwists and retwists the threads as a part of the thread uniting operation located below the level of the spools and laterally slidably in front of the spools so as to be brought into operative relation with respect thereto.

4. In a machine for winding and uniting threads, the combination of a plurality of supply spools, a plurality of winding spools, manually operated means for rendering the

winding spools individually inoperative, a thread uniting device which untwists and retwists the thread as a part of the thread uniting operation, and a guideway on the frame of the machine along which the thread uniting device is movable into operative relation with any desired pair of winding and supply spools, the thread uniting device being supported in and movable in a substan-

tially horizontal plane, no part of the guideway or thread uniting device being higher than the winding spools, thereby allowing the operator unobstructed access to all the spools. 10

In testimony whereof, we have signed our names to this specification. 15

TIMOTHY J. KELLY.
